(57) **CLAIM**

The ornamental design for a beverage container, as shown and described.

DESCRIPTION

FIG. 1 is a top perspective view of a first embodiment of a beverage container, showing our new design;

FIG. 2 is a bottom perspective view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top plan view thereof;

FIG. 8 is a bottom plan view thereof;

FIG. 9 is a top perspective view of a second embodiment of a beverage container, showing our new design;

FIG. 10 is a bottom perspective view thereof;

FIG. 11 is a front elevational view thereof;

FIG. 12 is a left side elevational view thereof;

FIG. 13 is a right side elevational view thereof;

FIG. 14 is a rear elevational view thereof;

FIG. 15 is a top plan view thereof;

FIG. 16 is a bottom plan view thereof;

FIG. 17 is a top perspective view of a third embodiment of a beverage container, showing our new design;

FIG. 18 is a bottom perspective view thereof;

FIG. 19 is a front elevational view thereof;

FIG. 20 is a left side elevational view thereof;

FIG. 21 is a right side elevational view thereof;

FIG. 22 is a rear elevational view thereof;

FIG. 23 is a top plan view thereof;

FIG. 24 is a bottom plan view thereof;

FIG. 25 is a top perspective view of a fourth embodiment of a beverage container, showing our new design;

FIG. 26 is a bottom perspective view thereof;

FIG. 27 is a front elevational view thereof;

FIG. 28 is a left side elevational view thereof;

FIG. 29 is a right side elevational view thereof;

FIG. 30 is a rear elevational view thereof;

(Continued)

FIG. 31 is a top plan view thereof; and, FIG. 32 is a bottom plan view thereof. The broken lines depict portions of the beverage container that form no part of the claimed design. The dash-dot broken lines represent boundaries of the design and form no part of the claimed design.

1 Claim, 28 Drawing Sheets
